UNITED STATES PATENT OFFICE.

EDWIN E. WOLF, OF NEW YORK, N. Y.

DESIGN FOR A DRESS.

Application filed January 26, 1924. Serial No. 8,425. Term of patent 3½ years.

To all whom it may concern:

Be it known that I, EDWIN E. WOLF, a citizen of the United States, and a resident of the city of New York, borough of Manhattan, in the county and State of New York, have invented a new, original, and ornamental Design for Dress, of which the following is a specification, reference being had to the accompanying drawing, forming part thereof, wherein the dress is distinguished by means of an ornamental band on the lower part of the blouse section of the dress as well as by vertically arranged orna-

mental sections of plaiting on the skirt at spaced intervals around the skirt.

Figure 1 is a front view of a dress, showing my new design.

Figure 2 is a rear view of the dress shown in Figure 1.

Figure 3 is an enlarged view of part of the ornamental band shown in Figure 1.

I claim:

The ornamental design for a dress, substantially as shown and described.

EDWIN E. WOLF.
